UNITED STATES PATENT OFFICE.

LEE YANCEY, OF CINCINNATI, OHIO, ASSIGNOR OF ONE-HALF TO J. H. RHODES, OF SAME PLACE.

STOCK-CAR.

SPECIFICATION forming part of Letters Patent No. 250,031, dated November 22, 1881.

Application filed August 18, 1881. (No model.)

To all whom it may concern:

Be it known that I, LEE YANCEY, a citizen of the United States, residing at Cincinnati, Hamilton county, Ohio, have invented new and 5 useful Improvements in Stock-Cars, of which the following is a specification.

My invention relates to railway-cars used in transporting live stock, its object being to facilitate the loading and care of animals in 10 transit, and to enable the car to be also conveniently used for transportation of ordinary merchandise at other times.

To this end my invention consists in providing the car with folding partitions of novel 15 construction, which divide the car into stalls, whereby the overcrowding and consequent injury of stock is prevented, which stalls may, when out of use, be folded up against the sides of the car, leaving the interior free for the storage of merchandise.

The invention embraces other features, which will be fully hereinafter described in detail, and specifically pointed out in the claims.

Referring, in aid of the description, to the 25 drawings illustrating and forming part of this specification, Figure 1 is a side elevation of a car embodying my invention, with the partitions folded. Fig. 2 is a plan section taken just beneath the roof or deck; Fig. 3, an enlarged cross-section, showing one of the partitions extended; Fig. 4, a cross-section of my improved floor; and Fig. 5 is a transverse sectional view, on an enlarged scale, through the feed-receptacle, taken on the line xx of Fig. 1.

In the figures of the drawings, A designates the floor of the car, B the roof, and C the uprights supporting the roof from the floor, the frame-work of the sides being substantially of the usual construction, and the uprights placed 35 apart about the proper distance for the width of the stalls.

The partitions P, hereinafter described, are preferably attached to and hinged upon alternate uprights C on both sides; but in fitting 45 up a car already constructed independent uprights may be inserted for the hinge-posts of the partitions and arranged either wholly on one side or alternating on opposite sides, as may be preferred.

Referring particularly to Fig. 3 for the con-

struction of the partitions, the hinge-post C (which may, as already explained, form one of the upright supports of the roof) is of square section for the lower part of its length and circular for the upper part. The partition consists, in the main, of three members, two of which, a b , are pivoted at c and operate on the lazy-tongs principle to support a third member, d , which latter forms the main bar across the car when the stalls are in use. 55

The manner of hinging the partition to the hinge-post is as follows: At the lower part of the post C is a U-shaped clip, e' , embracing the post at a rounded portion of the latter, and between the ends of the clip the member b is 60 pivoted horizontally. The member a is pivoted horizontally in a similar clip, e' , at the upper part of the hinge-post. The upper clip, e' , is arranged to slide vertically on the hinge-post, and both clips turn upon the post upon which 65 they form a hinge for the partition. It will readily be perceived that as the clip e' is pushed upward the members a and b draw together toward a vertical position. The third member, d , is provided with a longitudinal slot, in 70 which a pin or bolt, f , secured to and connecting it with the member b , is permitted to slide freely. The part d is also pivoted in the clip e , and is jointed at g . This arrangement permits the part d to double up when the clip e' 75 is pushed upward, and the whole partition to assume the position shown in Fig. 1, when it may be turned upon its hinge and caused to lie flat against the car-side, as shown in Fig. 2. When the partition is extended in use, the end 80 of the member d fits into a socket provided in the opposite upright, C, and the end of the member a into a similar socket upon or in the floor, thus holding the partition firmly in position.

In fitting up a car the hinge-posts C may be 85 simply iron rods, and may be arranged to slide laterally on suitable guides, so that all the partitions may, when desired, be pushed to either end of the car out of the way, and be adjusted to any desired width of stalls when in use. 90

It will be obvious that the partitions may be arranged to occupy diagonal positions to the car, if such is preferred, suitable sockets being provided for the ends of the members a and b . 95

The floor of the car may be constructed as 100
